UNITED STATES PATENT OFFICE.

ELBERT NICHOLSON, OF STURGIS, MICHIGAN.

FIREPLACE-HOOD.

1,118,146.

Specification of Letters Patent.

Patented Nov. 24, 1914.

Application filed December 10, 1913. Serial No. 805,806.

To all whom it may concern:

Be it known that I, ELBERT NICHOLSON, a citizen of the United States, residing at Sturgis, Michigan, have invented certain new and useful Improvements in Fireplace-Hoods, of which the following is a specification.

This invention relates to improvements in fireplace hoods.

10 My invention relates particularly to the damper features of the hood.

15 The main object of this invention is, to provide an improved fireplace dome and damper which may be easily set and adjusted so that the damper actuating hand piece may be brought to any desired positions either in the front wall or side wall of the fireplace or mantel.

20 Further objects relating to details and economies of structure and operation will definitely appear from the detailed description to follow.

25 I accomplish the objects of my invention by the devices and means described in the following specification.

The invention is clearly defined and pointed out in the claims.

30 A structure which is a preferred embodiment of my invention is clearly illustrated in the accompanying drawing forming a part of this specification, in which:—

35 Figure I is a detail vertical section from front to rear through a fireplace structure embodying features of my invention. Fig. II is a longitudinal section through the hood proper on a line corresponding to line 2—2 of Fig. I. Fig. III is a detail plan view of my improved fireplace hood, the bracket 24 and worm being omitted. Fig. IV is an 40 end elevation looking from the right of Fig. III. Fig. V is an enlarged detail section on a line corresponding to line 5—5 of Fig. III. Fig. VI is a transverse section on a line corresponding to line 6—6 of Fig. III. Fig. VII is an enlarged detail section showing the wall socket 34 and the finger piece 25 associated therewith. Fig. VIII is an 45 enlarged detail end elevation of the adjustable bracket 24 from the right hand of Fig. II. Fig. IX is a detail sectional view of the structure with the spur gear adjusting pinion in place taken on a line corresponding to line 1—1 of Fig. II.

In the drawing similar reference characters refer to similar parts throughout the several views, and the sectional views are

taken looking in the direction of the little arrows at the ends of the section lines.

Referring to the drawing, 1 represents a fireplace of common construction having a 60 flue 2. Across the front of the fireplace is an angle bar supporting ledge 3. The end walls 4 and 5 of the hood are provided with the base flanges 6 adapted to rest on suitable ledges or shoulders formed by the lining brick of the fire-place as in the structure shown or as otherwise may be provided. The front wall 7 of the dome rests upon the supporting ledge 3. The rear ends of the side walls are connected by the angle 65 bar 8 which is bolted to suitable angle flanges 9 on the inner sides of the end walls. The front wall 7 is bolted to suitable flanges 10 on the end walls. The reinforcing bars 11 and 12, preferably of angle iron, are 70 bolted to the front wall 7 to reinforce the 75 same.

The damper 13 is provided with journals 14 and 15 disposed in suitable bearings 16 and 17 of the end walls 4 and 5 respectively. 80 A gear 18 is arranged on the journal 17 and secured to the damper so that the damper is rotated thereby. Lugs 19 on the gear 18 engage the end of the damper. The gear 18 is provided with a stop pin 20 which contacts with a flange-like stop 21 on the adjacent end wall, the stops being disposed to engage when the damper is opened. When it is desired to control the damper from the front of the fireplace the gear is actuated 85 through the worm 22 which is provided with a square spindle or actuating rod 23. This spindle 23 is journaled in the bracket 24 which is adjustably mounted on the end wall 5 to permit the spindle being swung to the 90 desired position to bring the finger piece 25 of the spindle into the position desired and also to permit the spindle being disposed so that it will pass between facing 95 bricks or tiles instead of necessitating the 100 breaking of such bricks or tiles.

To provide for the convenient adjustment of the bracket 24 the end wall 4 is slotted at 26, 27 and 28, the slots being segmental. The supporting bolts 29 of the 105 bracket are arranged in these slots. The upper edge of the end walls is curved at 30, while the bracket is provided with a rib 31 having lug portions 32 bearing or engaging the curved portion of the wall, thus assisting the bolts in supporting the bracket. The bracket is provided with a hole in which 110

the bolts 29 may be arranged as necessary to secure the desired adjustment. With the parts thus arranged the actuating spindle may, as stated, be positioned as desired, and arranged between the facing tile or brick. The teeth of the gear are preferably tapered so that the worm may be swung to some extent sidewise of the pinion without interfering with its effective and easy operation.

16 The wall socket 34 is provided with a concave seat 35 for the face 36 of the finger piece 25. This permits the swinging of the spindle and at the same time the finished appearance of the finger piece is retained.

15 When it is desired to control the damper from the side I substitute a small pinion 37, see Fig. IX for the worm 22. The square spindle is then inserted through bearing hole 33, see Figs. IV, VIII and IX. A

20 hole is made in the side wall of the fire place to receive it, the same as before, and the adjustment of the bracket enables the proper location.

I have illustrated and described my improvements in detail in the form in which I have embodied the same for the market. I have not attempted to illustrate or describe the certain modifications and variations in structural details, which I contemplate, as I believe the disclosure made will enable those skilled in the art to embody my improvements as conditions may require. I desire, however, to be understood as claiming my improvements specifically in the form illustrated as well as broadly within the scope of the appended claims.

Having thus described my invention, what I claim as new and desire to secure by Letters Patent is:

40 1. In a structure of the class described, the combination with a dome comprising end walls, a damper journaled in said end walls, the upper edge of one of the end walls being curved, said end walls having segmental 45 slots therein, the slots and curved edge being concentric with the axis of the damper, an actuated gear on said damper, a supporting bracket having spaced spindle supporting ears and parts engaging the curved upper edge of said end wall, bolts engaged in said slots whereby the bracket is supported for adjustment concentrically of the damper axis, an actuating gear disposed between said spindle supporting ears to coact with said actuated gear, and an actuating spindle arranged through said supporting ears and actuating gear for axial adjustment.

2. In a structure of the class described, the combination with a dome comprising end 60 walls, a damper journaled in said end walls, one of said end walls having segmental slots therein concentric with the axis of the damper, an actuated gear on said damper, a supporting bracket having spaced spindle 65 supporting ears, bolts engaged in said slots

whereby the bracket is supported for adjustment concentrically of the damper axis, an actuating gear disposed between said spindle supporting ears to coact with said actuated gear, and an actuating spindle arranged through said supporting ears and actuating gear for axial adjustment.

3. In a structure of the class described, the combination with a dome comprising end walls, a damper journaled in said end walls, an actuated gear on said damper, a supporting bracket having spaced spindle supporting ears supported for adjustment concentrically of the damper axis, an actuating gear disposed between said spindle supporting ears to coact with said actuated gear, and an actuating spindle arranged through said supporting ears and actuating gear for axial adjustment.

4. In a structure of the class described, the combination with a dome comprising end walls, of a damper journaled in said end walls, an actuated gear at one end of said damper, an actuating gear coacting with said actuated gear, a supporting bracket for said actuating gear mounted on the end wall adjacent to the actuated gear for adjustment concentrically of said actuated gear, and an actuating spindle for said actuating gear slidably engaged therewith and with said supporting bracket, all coacting for the purpose specified.

5. In a structure of the class described, the combination with a dome, of a damper journaled in said dome, an actuated gear operatively associated with said damper, an actuating gear coacting with said actuated gear, a supporting bracket for said actuating gear mounted on said dome for adjustment concentrically of said actuated gear, a spindle for said actuating gear axially adjustable relative thereto, and a finger piece for said spindle provided with ball and socket members, all coacting for the purpose specified.

6. In a structure of the class described, the combination with a dome, of a damper journaled in said dome, an actuated gear operatively associated with said damper, an actuating gear coacting with said actuated gear, a supporting bracket for said actuating gear mounted on said dome for adjustment concentrically of said actuated gear, a spindle for said actuating gear, and a finger piece for said spindle provided with ball and socket members, all coacting for the purpose specified.

7. In a structure of the class described, the combination with a dome, a damper journaled in said dome, an actuated gear operatively associated with said damper, an actuating worm gear coacting with said actuated gear, a supporting bracket for said actuating gear mounted on said dome for adjustment concentrically of said actuated

gear, and a spindle for said actuating gear axially adjustable relative thereto, all co-acting for the purpose specified.

8. In a structure of the class described, 5 the combination with a dome, a damper journaled in said dome, an actuated gear operatively associated with said damper, an actuating gear coacting with said actuated gear, a supporting bracket for said actuating gear mounted on said dome for adjust-

ment concentrically of said actuated gear, and a spindle for said actuating gear, all coacting for the purpose specified.

In witness whereof, I have hereunto set my hand and seal in the presence of two witnesses. 15

ELBERT NICHOLSON.
